DISPLAY STAND

Charles O. Larson, Sterling, Ill. 61081

Filed Nov. 23, 1970, Ser. No. 26,107

Term of patent 14 years

Int. Cl. D6—06

U.S. Cl. D80—9

FIG. 1 is a perspective view of a display stand of my design;

FIG. 2 is a top plan view thereof; and

FIG. 3 is a cross sectional view taken on line 3—3 of FIG. 1.

The broken line representation of merchandise and support hooks therefor in FIG. 1 is for purpose of illustration only. In addition, it is to be understood that some of the perforations have been omitted from the display panels for convenience of illustration.

I claim:

The ornamental design for a display stand, substantially as shown and described.
